UNITED STATES PATENT OFFICE.

EARL V. MOREIS, OF BIG LAKE, TEXAS.

AIR WASHER FOR INTERNAL-COMBUSTION ENGINES.

Application filed September 21, 1926. Serial No. 136,885.

This invention aims to provide novel means whereby air may be washed and filtered before it is delivered to the carburetor of an internal combustion engine.

5 It is within the province of the disclosure to improve generally and to enhance the utility of devices of that type to which the invention appertains.

With the above and other objects in view 10 which will appear as the description proceeds, the invention resides in the combination and arrangement of parts and in the details of construction hereinafter described and claimed, it being understood that 15 changes in the precise embodiment of the invention herein disclosed, may be made within the scope of what is claimed, without departing from the spirit of the invention.

20 In the drawings:—

Figure 1 shows in elevation, a portion of an internal combustion engine whereunto the device forming the subject matter of this application has been applied, parts appearing in section;

Figure 2 is a longitudinal section of the attachment;

Figure 3 is a cross section on the line 3—3 of Figure 2;

30 Figure 4 is a cross section on the line 4—4 of Figure 2.

In Figure 1 of the drawings, there is shown an internal combustion engine provided with a carburetor 1. The radiator extension is shown at 2, and the numeral 3 designates the over-flow pipe for the radiator. The securing elements which hold the cylinder head on the engine block are marked by the numeral 4.

40 In carrying out the invention, there is provided a plate-like bracket 5 which is held by the securing elements 4 on the framework of the engine, the bracket 5 including a ring 6 within which extends the tubular body 7 of a receptacle 8, the receptacle including a lid 9 mounted on the body 7. The body 7 is provided near to its lower end with a circumferential stop bead 30 against which abuts the cup-like bottom of the receptacle 8, the bottom 10 having a stem 11 received slidably in a guide strip 12 that is extended across the body 7, the upper end of the stem 11 being threaded into a bridge 14 which extends across the body 7. The body 50 7 has trunnions 15 mounted to rock in the ring 6, and enabling the receptacle 8 to be

adjusted in position, to accommodate itself readily to certain flues and pipes, for instance, to an air flue 16, the lower end of which is connected to the air intake of the carburetor, the upper end of the air flue 16 being connected to an elbow 17 that is mounted on the lid 9.

In the upper end of the receptacle 8 there is located a distributing head 18, preferably in the form of a perforated coil, one end of the coil extending outwardly through the lid 9, the said end of the coil being secured in the lid 9. One end of a tube 19 is mounted on the exposed portion of the coil 18, the other end of the tube 19 being connected to a nipple 20 which is mounted in the radiator extension 2, the overflow pipe 3 being shortened enough so that there is a vapor chamber 31 of sufficient capacity in the extension 2, above the level of the water in the radiator. The coil or distributor head 18 preferably is open at its lower end.

A cup 21 is mounted on the elbow 17 and carries a valve mechanism 22 which limits the flow of liquid out of the cup 21. Screens 23 are mounted removably in the body 7 of the receptacle 8, below the distributing head or coil 18. Filtering material of any desired sort, marked by the numeral 24, is disposed between the screens 23.

The body 7 of the receptacle 8 is supplied with a lateral air inlet pipe 25, the outer end of the inlet pipe being covered by a screen 26. The air inlet pipe 25 discharges into an inverted trough-shaped apron 27 carried by the side wall of the body 7 of the receptacle, the apron 27 having a deflecting end wall 28 which is inclined a little with respect to the vertical.

Air enters the inlet 25 through the screen 26, and the screen 26 picks out the very coarse matter which may be in the air. The air is deflected downwardly by the part 28 and is directed against a mixture of oils 29 which is carried by the cup-like bottom 10. It is to be observed that the stem 11 may be threaded out of the bridge 14, thereby permitting the bottom 10 to be removed, for the renewal of the oily material 29 therein. The air proceeds, and passes through the screen 23 and through the filtering material 24. The cup 21 contains turpentine or some other substance which aids in keeping down carbon. The turpentine or other liquid in the cup 21, drops downwardly into the filtering material at 24. Owing to the fact that

the distributing head 18 is in the form of a coil, the turpentine or other material may drop downwardly from the cup 21 into the filtering material 24, without fouling the distributing head 18 and closing the openings or perforations in the said head. In view of the fact that the turpentine or other material is discharged as aforesaid upon the filter 24, the air is charged with the contents of the cup 21, as the air passes upwardly through the filtering material 24. In the space 32 which exists above the uppermost screen 23, the air comes into contact with vapor from the radiator, the vapor passing from the vapor chamber 31, through the tube 19, and being distributed by the coil 18, in the space shown at 32, the vapor passing outwardly through the perforations of the coil 18.

20 The air, deprived of dust, charged with vapor, and carrying some of the material from the cup 21, moves through the flue 16, and enters the carburetor 1, the performance of the engine being improved accordingly.

25 What is claimed is:—

1. In a device of the class described, a receptacle provided at its upper end with an air outlet, and supplied near to its lower end with an air inlet, a filter in the receptacle between the inlet and the outlet, a distributing head in the receptacle above the filter, means for supplying vapor to the head, and a liquid container discharging downwardly on the filter, the head being centrally opened so that the container can 35 discharge downwardly therethrough.

2. In a device of the class described, a receptacle provided at its upper end with an air outlet, and supplied near to its lower end with an air inlet, a filter in the receptacle between the inlet and the outlet, a distributing head in the receptacle above the filter, means for supplying vapor to the head, and a detachable cup-like bottom for the receptacle, the air inlet embodying a deflector for directing the incoming air into the cup-like bottom.

3. In a device of the class described, a receptacle provided at its upper end with an air outlet and supplied near to its lower 50 end with an air inlet, a filter in the receptacle between the inlet and the outlet, a liquid container discharging downwardly on the filter, the receptacle being provided with a detachable cup-like bottom, and the air 55 inlet embodying a deflector for directing the incoming air into the cup-like bottom.

In testimony that I claim the foregoing as my own, I have hereto affixed my signature.

EARL V. MORRIS.
